[57] CLAIM

The ornamental design for a support base for a computer, as shown and described.

DESCRIPTION

FIG. 1 is an elevational perspective view of the support base for a computer of the present invention;

FIG. 2 is a front end view of the support base for a computer shown in FIG. 1;

FIG. 3 is the rear end of the support base for a computer shown in FIG. 1;

FIG. 4 is a top view of the support base for a computer as shown in FIG. 1;

FIG. 5 is a bottom view of the support base for a computer as shown in FIG. 1;

FIG. 6 is a left side view of the support base for a computer as shown in FIG. 1; and,

FIG. 7 is a right side view of the support base for a computer as shown in FIG. 1.

FIG. 1

FIG. 2

FIG. 3

FIG. 4

FIG. 5

FIG. 6

FIG. 7
